UNITED STATES PATENT OFFICE.

JACOB W. FIELD, OF PEORIA, ILLINOIS.

TICKET-VENDER.

1,303,278.

Specification of Letters Patent. Patented May 13, 1919.

Application filed January 2, 1918. Serial No. 210,083.

To all whom it may concern:

Be it known that I, JACOB W. FIELD, citizen of the United States, residing at Peoria, in the county of Peoria and State of Illinois, 5 have invented certain new and useful Improvements in Ticket-Venders; and I do hereby declare that the following is a full, clear, and exact description of the invention, which will enable others skilled in the art 10 to which it appertains to make and use the same.

This invention relates to ticket venders of that type wherein a ribbon of paper in the form of a series of separable tickets is arranged to be positively fed beneath a window so that said tickets are discernible one 15 at a time and adapted to be projected from the vender in a position to be detached from the ribbon one by one.

20 One of the objects of the invention is to furnish a ticket vender for selling merchandise of different values at a uniform price by means of tickets, each designating a specific article of sale, the prospective purchaser 25 being enabled to view each ticket before its purchase through an opening or window.

Another object of the invention is to provide a novel means for positively projecting a ticket strip from the cabinet in which 30 it is contained a distance equal to the length of one of the tickets to a position where the tickets may be separated one by one from the said ticket strip, and provide means for preventing retrograde movement of the strip 35 after having been moved by the ejecting means.

Besides the above objects the invention relates to certain details of construction and arrangement of parts such as will be clearly 40 pointed out herein and form the subject of certain of the appended claims.

In the accompanying drawings, forming a part of this application,

Figure 1 is a longitudinal sectional elevation of a cabinet, showing a ticket reel and my invention used therewith.

Fig. 2 is an elevation of the front of the cabinet, part being shown in section.

Fig. 3 is a plan of a portion of the same.

50 Fig. 4 shows, in perspective, parts entering into the construction of my device.

Fig. 5 also shows, in perspective, certain parts of my said device.

Fig. 6 is a longitudinal section of a part 55 of the cabinet, on a greatly enlarged scale, showing my invention attached thereto.

Fig. 7 is a front elevation of a part of the cabinet on a still larger scale.

Figs. 8 and 9 show a modification of a part for assisting in preventing retrograde 60 movement of the ticket strip within the vender.

My ticket vender consists of one or more reels of tickets in the form of a ticket-strip, each ticket having a specific article of sale 65 designated thereon, said reel or reels of tickets being inclosed in a suitable cabinet, one end of the strip being adapted to be projected through an opening in the wall of the cabinet, a small window preferably 70 the size of a ticket permitting the purchaser to view each ticket before purchasing it. The ticket strip is preferably punched at regular intervals to be engaged by a member for positively moving the ticket strip one 75 ticket at a time from the cabinet, there being means to prevent movement of the ticket strip in a direction opposite that in which it is fed as will more readily appear from the following:

A represents the inclosure or cabinet of the vender and B the lid or cover for the same which may be secured thereto in any suitable manner. Secured to the under side of the lid or cover in any desired manner is 85 a support for holding one or more reels of paper strip B' which strip I term a "ticket-strip." Said support in the present instance consists, for convenience, of two members C, Fig. 2, having a connecting cross 90 member D at their lower ends, which may rest upon the bottom of the cabinet, if desired. A shaft E extends through the support C for carrying the said reels.

Beneath the lid or cover B is a guide 95 clearly shown in Fig. 4 by the reference character G. This may preferably be in the form of a U having extended flanges H at its longitudinal edges adapted to be secured to the under side of said lid or cover. 100

Extending longitudinally of the guide is a groove J created by depressing the metal of which the guide is formed and at the inner or rear terminus of the groove is a pointed tongue K struck up from the metal, the 105 free extremity of which is slightly raised and points in the direction of the front of the cabinet, see Fig. 5.

Rearward of the tongue K the guide is bent downwardly into the tongue L over 110 which the ticket strip is adapted to be drawn. Lying upon and within the guide

is a slide M. This is preferably corrugated longitudinally at N in order to give it strength and in order that it will hold its proper straight form. Centrally the slide 5 is provided with a corrugation O arching over the described groove J of the guide G. This arching of the slide permits the tongue K to extend up into the groove so that its point will readily engage in the perforations 10 of the ticket strip. The said ticket strip is perforated along its medial line at regular intervals as B², each perforation being on the margins of adjoining tickets as clearly shown in Fig. 4. When one of the perforations 15 of the ticket strip reaches the tongue K the point of that member must necessarily engage the perforation between the tickets due to the fact that the slide holds the edges of the strip down upon the guide at 20 each side of the groove J while the medial portion must pass over the tongue at a higher elevation. This arches the strip so that when a perforation comes opposite the tongue said strip drops over the tongue, the 25 latter engaging in the perforation. The relation of the tongue and strip is shown in Figs. 5 and 7.

The forward end of the slide is furnished 30 with a downwardly bent tongue P adapted to move within the groove J of the guide G and consequently it is in position to engage the ticket strip by entering any one of the perforations thereof, see Figs. 4 and 7.

The lid or cover above the guide G is provided 35 with a slot Q lying parallel to the ticket strip. A member R is secured to the slide M and extends up through the described slot and is provided with a finger-piece S. At the forward end of the lid or 40 cover is an opening T covered by a transparent plate U forming a window, a suitable frame V being preferably secured upon the lid or cover to retain the said plate in position.

45 The length of the slot Q is such as to permit the slide to move a distance substantially equal to or slightly more than the distance between two of the perforations in the ticket strip or a distance substantially 50 equal to the length of a single ticket. In moving the finger-piece S along the slot to eject a ticket the tongue P of the slide normally riding upon the ticket strip drops into one of the perforations carrying said strip forward ejecting one ticket at each movement of said finger-piece and slide. The limit of forward movement of the slide is shown in broken lines in Fig. 6, the finger-piece striking the frame V, for example, the ejected ticket being torn off across the perforation at the front of the cabinet, the outer ends of the guide G or the depending edge of the said frame V being used as the tearing edge.

65 The slide is permitted sufficient vertical

movement, of course, to allow its tongue P to drop into a perforation in the ticket strip and ride out of it as it is moved back and forth.

The position of the tongue K, it will be 70 observed, is such that one of the perforations of the ticket strip will now be engaged by it so that when the slide is moved back to the normal position shown in unbroken lines, the friction between the tongue P and said strip cannot result in carrying the strip back with it, the ticket just positioned beneath the opening T and its window being permanent until the slide is again brought 75 forward to eject it.

In Figs. 8 and 9 I show another form of device for preventing the retrograde movement of the ticket strip. That is to say, I show a member W having a downturned portion forming an obtuse angle to that part 80 of the strip forward of it provided with serrations 2. The opposite edge of said member is mounted on the under side of the guide G, for example, the said serrations 2 projecting through an opening 3 in said 85 guide G to engage the under side of the ticket strip and using the slide M as a backing and for receiving pressure of the ticket strip against it. Said member W may be 90 of spring metal for providing the necessary pressure on the ticket strip, or a spring 4 shown in Fig. 8 may be used for accomplishing the same result.

The support C and its parts in being suspended from the lid or cover B permits the 100 whole structure being removed bodily from the cabinet for inspection and adjustment and for the purpose of renewing the reels of ticket strip as occasion requires, which is a convenience as well as greatly simplifying 105 the structure besides which there is little likelihood of chance disarrangement of the parts.

110 Preferably it is the wish to employ a movable part such as the slide M or its equivalent having a portion such as the tongue P or its equivalent for positively engaging the ticket strip. By this means said strip if provided with perforations will be positively moved or if said tongue is sharp so as to "bite" into 115 the strip, though the engagement with a perforation is, perhaps, to be preferred. This results in an absolutely positive feed of the strip a distance equal to the length of one ticket as has been described, any suitable and 120 efficient means, such as those described, or the equivalent, being used to prevent the inward or retrograde movement of the strip.

I may make slight changes in the entire arrangement of my vender without departing from the spirit and intent of the invention or the appended claims.

Having thus described my invention, I claim:—

1. The combination in a device for vend- 130

- ing separate detachable portions of a longitudinally perforated strip, of mechanism including a guide for receiving and guiding said strip, said guide including a tongue 5 struck up therefrom pointing in the direction in which the strip travels, its point extending above the surface upon which the strip lies whereby said strip as it lies thereon is arched in a transverse direction, and a slide 10 resting upon the strip having a tongue directed toward the strip in the same direction as the first described tongue, said slide adapted to carry the strip down over the tongue as one of the perforations overlies it.
- 15 2. A vending device including in its construction a trough shaped guide having a continuous depression extending longitudinally of its bottom, and also having a tongue in its bottom having a raised extremity 20 pointing in the direction of one end of said guide, and a member slidable within said guide including a tongue pointing in the same direction as the first said tongue and depending into said depression.
- 25 3. A vending device including in its construction two portions, one of them having a depression extending longitudinally thereof, and also having a tongue struck up therefrom pointing toward one end of such portion, the other portion being slidable upon the first and having a tongue depending into said depression pointing in the same direction as the first described tongue.
- 35 4. A vending device including in its construction two portions, one of them having a trough shape provided with a longitudinal depression and having an upwardly bent tongue whose free extremity points in the direction of one end, the other portion con- 40 stituting a slide within the first and provided with a downwardly bent tongue pointing in the same direction as the other to travel within said depression.
- 45 5. A vending device including in its construction a guide for a ticket strip having a series of perforations extending longitudinally thereof, including a depression extending longitudinally of the same over which the strip lies, and also including a tongue at 50 one end pointing toward its other end to engage in one of the perforations, and a member overlying the strip having a tongue extending in the same general direction as the first named tongue adapted to engage in one 55 of the perforations and depending into the depression.
- 60 6. A vending device including in its construction a guide including a depression extending longitudinally of the same and also including a tongue at one end pointing toward its other end, and a member having a tongue extending in the same general direc-
- tion as the first named tongue and depending into the depression.
7. A vending device including in its construction two portions, one of them having a longitudinal depression and also having a tongue at one end upturned and pointing in the direction of its other end, the other portion adapted to move above the first portion 65 in a longitudinal direction, having a groove in its surface lying nearest the said first portion and also having a tongue turned in the direction of the same and pointing in the same directions as the first named tongue. 70
8. A vending device including in its construction a support, and two portions, one of them secured to said support and having a longitudinal depression and also having a tongue at one end upturned and pointing in the direction of its other end, the other portion adapted to move above the first portion 75 in a longitudinal direction, having a groove in its surface lying nearest the said first portion and also having a tongue turned in the direction of the same and pointing in the same directions as the first named tongue. 80
9. A vending device including in its construction a support, a trough shaped guide secured to its under side having at one end a tongue upturned toward the support and pointing in the direction of its other end, a member within the guide having a tongue downturned toward the guide and pointing in the same direction as the first said tongue, means to shift the member with respect to the guide, and means to limit its shifting 90
- 95
10. A vending device including in its construction an inclosure for a longitudinally perforated strip, a guide through which to direct said strip having a groove extending along its bottom forming a longitudinal depression, and also having a tongue to engage one of the perforations of the strip to prevent the movement of the latter in one direction, and a manually operated member having a depending portion extending down into said groove and adapted to move along the same and to engage in one of the perforations of said strip, said manually operated member being grooved longitudinally to 105 form an arched portion, the said tongue of the guide extending up into said arched portion. 110
- 115

In testimony whereof I affix my signature, in presence of two witnesses.
